DESIGN FOR A ROTARY DUPLICATING MACHINE

Willis A. Kropp, Oak Park, Ill., assignor to Ditto,
Incorporated, Chicago, Ill., a corporation of
West Virginia

Application November 11, 1937, Serial No. 72,801

Term of patent 7 years

To all whom it may concern:

Be it known that I, Willis A. Kropp, a citizen
of the United States, residing at Oak Park, in
the county of Cook and State of Illinois, have in-
vented a new, original, and ornamental Design
for a Rotary Duplicating Machine, of which the
following is a specification, reference being had to
the accompanying drawings, forming part there-
of, in which—

Fig. 1 is a perspective view of a rotary duplicating machine showing my new design; and

Fig. 2 is a perspective view of the machine from the opposite side.

I claim:

The ornamental design for a rotary duplicating machine, as shown.

WILLIS A. KROPP.
